[57] CLAIM

The ornamental design for a jewelry organizer, as shown and described.

DESCRIPTION

FIG. 1 is a front elevational view of a jewelry organizer showing my new design;

FIG. 2 is a top plan view thereof;

FIG. 3 is a bottom plan view thereof;

FIG. 4 is a left side elevational view thereof;

FIG. 5 is a right side elevational view thereof; and

FIG. 6 is a rear elevational view thereof.

The broken-line depiction of various elements of jewelry in FIGS. 1 and 4 is for illustrative purposes only and forms no part of the claimed design.
